(57) **CLAIM**

The ornamental design for a wallet, as shown and described.

DESCRIPTION

FIG. 1 is a front, right and top perspective view of a wallet, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a partial enlarged view of an area labeled 9 in FIG. 2; and,

FIG. 10 is a partial enlarged view of an area labeled 10 in FIG. 2.

The dot-dash broken lines in FIGS. 2 and 9-10 depict the boundaries of the enlargements that form no part of the claimed design.

1 Claim, 10 Drawing SheetsFIG. 1

FIG.2

FIG.3

FIG. 4

FIG.5

FIG.6

FIG.7

FIG.8

FIG. 9

FIG.10
